UNITED STATES PATENT OFFICE.

FRANK R. KELLEY, OF PITTSBURGH, PENNSYLVANIA.

VENTILATOR.

Application filed November 30, 1923. Serial No. 677,733.

The present invention relates to ventilators for factories, office buildings, churches, schools, etc.

The object of the present invention is to 5 augment a standard type of ventilator by an addition to the outlet terminus of the cowl in order to effect an increased efficiency the degree of which varies in harmony with the wind velocity.

10 A co-ordinate object of the invention is to provide an improved cowl attachment affixed to the exhaust end of the cowl and disposed at a predetermined angle to eliminate possibility of the air, which passes over 15 the cowl, from meeting with varying resistances emanating from wind pressure and eddy currents.

Other objects of the invention will be 20 apparent from the following description of the present preferred form of the invention taken in connection with the accompanying drawings wherein:—

Fig. 1 is a side elevational view of a ventilator constructed in accordance with this 25 invention and

Fig. 2 is an end elevational view of the same.

The ventilator constructed in accordance with this invention consists of a base tube 30 3 which may be of standard construction and has a cowl 4 mounted thereon. The cowl in the present instance is shown to be of the usual elbow shaped type usually employed for the ventilation of buildings and 35 is modified in a manner hereinafter set forth to include the device of the present invention.

A frusto-conical tube 5 is mounted in the cowl 4 and disposed at an inclination so that 40 wind will be directed toward the upper end of the cowl. The enlarged end of the tube is arranged to lie outside of the cowl while the reduced end terminates at approximately the longitudinal center of the tube 3. A spindle 6 also of substantially standard 45 construction is mounted in the tube 3 and secured to the cowl 4 to serve as an axis for the latter in a manner well known in the art. This spindle passes through the lower 50 portion of the reduced terminal of the tube 5 and impinges the terminal of the upper part of said tube as shown in Fig. 2. The tube 5 capacitates as an ejector to function in expelling air, smoke or the like through 55 the cowl in a well known manner. The particular manner of mounting the ejector, as

above recited, is important in order that the greatest amount of efficiency may be derived from a cowl constructed in accordance with the present invention as will be more 60 apparent from the subsequent description of another portion of the cowl.

The outlet end 7 of the cowl is disposed at an angle to the axis of the cowl and is equipped with a bell shaped body or flange 8. The free marginal edge of this bell shaped member is also disposed at an inclination which in actual practice is at an angle of about 45 degrees to the axis of the cowl. The upper part of the member 8 is 70 relatively wider than the lower part so that the angle of the outer end thereof is formed by the inherent construction of this member rather than by making the member of a uniform width and receding the lower end 75 thereof inwardly on the cowl, which however may be done if found preferable. It is of importance however that the ratio of the upper end of said bell shaped member or flange to the lower end be about two to 80 one in order to eliminate eddy currents around the upper portion of the outlet end of the cowl that is in the path of the wind ejected through the ejector tube 5. The bell shaped member 8 may be either attachable to or made integral with the outer end of the cowl 4. The bell shaped member also deflects the air, passing around the outside of the cowl, away from the air exhausted through the latter thereby preventing the 85 formation of static air pressure at the exhaust end of the cowl.

A vane 9 is secured to the top of the cowl 4 and is adapted to be impinged by the wind in the usual manner so as to maintain the 90 ejector tube 5 in the path of the wind at all times. The vane may be of the usual or any desired construction.

The arrangement of the ejector and the construction and arrangement of the bell shaped flange 8 positively eliminates the 100 possibility of air passing over the cowl from meeting with varying resistances caused by wind pressure and eddy currents. It has been developed on test that the addition of 105 the bell shaped flange and arrangement of the ejector as herein set forth adds approximately 23 per cent efficiency to the ventilator at a four mile wind velocity. Furthermore 110 the cowl additions contemplated by the present invention are exceedingly simple so as to reduce the cost thereof to a minimum

and may be used for an indefinite period of time without attention or replacement.

It is of course understood that the cowl may be otherwise modified to effect some-
5 what similar results to that obtained by the device above described. It is to be under-
stood however that the present invention contemplates a device which will positively
10 eliminate eddy currents at the outlet end of the cowl and otherwise augment the utility
of the latter so as to effect a materially in-
creased efficiency without appreciably in-
creasing the cost of manufacture of the
ventilator.

15 What is claimed is:

1. In a ventilator of the character de-
scribed, the combination of a base, a curved
cowl rotatably mounted on said base, an in-
jector tube extending into said cowl from
20 the rear and having its outlet directed up-
wardly towards the mouth of said cowl, and
an edged flange for the mouth of said cowl
flaring upwardly and outwardly therefrom at
25 an abrupt angle and diminishing downward-
ly in width, for the purpose of causing air
currents traveling over said cowl to bound
upwardly to produce an aspirating effect at
the mouth of said cowl in the presence of
30 low wind velocities.

2. In a ventilator of the character de-
scribed, the combination of a base, a curved
cowl rotatably mounted on said base, an in-

jector tube extending through the rear of
said cowl and having its outlet directed up-
wardly toward the mouth of said cowl, and
35 a flaring flange surrounding the mouth of
said cowl and having its outer edge lying in
a plane converging downwardly towards the
axis of rotation, said flange extending out-
40 wardly at an abrupt angle from the cowl
whereby the air currents traveling over the
cowl are caused to bound upwardly and pro-
duce an aspirating effect at the mouth of
45 said cowl in the presence of low wind ve-
locities.

3. In a ventilator of the character de-
scribed, the combination of a base, a curved
cowl rotatably mounted on said base, an in-
jector tube extending through the rear of
50 said cowl and having its outlet directed up-
wardly toward the mouth of said cowl, and
a flaring flange surrounding the mouth of
said cowl and having its outer edge lying
55 in a plane converging downwardly towards
the axis of rotation, said flange extending
outwardly at an abrupt angle from the cowl
whereby the air currents traveling over the
cowl are caused to bound upwardly and pro-
60 duce an aspirating effect at the mouth of
said cowl, the area of said flange diminish-
ing downwardly.

In testimony whereof I affix my hand.

FRANK R. KELLEY.
